ATTORNEY.

UNITED STATES PATENT OFFICE.

THEODORE METZELER AND FREDERICK DENIVELLE, OF NEW YORK, N. Y.

DESIGN FOR A STATUETTE.

No. 37,735.

Specification for Design.

Patented Dec. 19, 1905.

Application filed April 15, 1905. Serial No. 255,853. Term of patent 7 years.

To all whom it may concern:

Be it known that we, THEODORE METZELER, residing at 300 Eleventh street, and FREDERICK DENIVELLE, residing at 401 Dean street, in the borough of Brooklyn, city of New York, county of Kings, State of New York, citizens of the United States, have invented a new, original, and ornamental Design for a Statuette, of which the following is a full and exact specification.

The figure is a perspective drawing, showing the design of the statuette.

We claim—

The ornamental design for a statuette as shown.

THEODORE METZELER.
FREDERICK DENIVELLE.
